ROTATION COUNTER FOR VERTICAL PRINTING PRESSES

Joseph F. Garito, 20 Stewart St., Lowville, N.Y.; Harold J. Foster, Lowville, N.Y. (Castorland, N.Y.); and Lloyd E. Tiffany, Lowville, N.Y. (R.F.D. 1, Glenfield, N.Y.)

Filed Feb. 16, 1959, Ser. No. 793,345

4 Claims. (Cl. 101—269)

This invention relates to improvements in rotation counters for vertical printing presses of the commercially designated "Miehle" type well known in the art, and in which an impression cylinder moves upwardly from a lowered idle position during its cycle of operation and is stopped in a full cycle raised position against rotation by stop mechanisms such as that shown in U.S. Patent No. 2,305,851, dated December 22, 1942.

By way of premise, rotation counters for the impression cylinder of such printing presses have been provided but are usually located on the cylinder and move up and down and rotate therewith so that under high speed operation of such presses it is very difficult to read such counters and to read the same at all an operator must stand very close to the press in a precarious position.

Having the foregoing in mind, the primary object of this invention is to provide a rotation counter for the impression cylinder of such presses which is mounted on the press remote from the cylinder in a fixed position for operation in response to rotation of the cylinder into full cycle position and upward movement thereof, so that said counter may be easily read by an operator at a safe distance from the press.

Another object is to provide a rotation counter as in the foregoing which is operated primarily by means of the aforesaid stop mechanism for the cylinder, whereby to utilize a standard part of such presses as a prime operating means for the counter.

Still another object is to provide a counter according to the foregoing, and means of simple form and inexpensive construction operatively connecting the stop mechanism to the counter.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary view in side elevation of the invention in a preferred embodiment thereof;

Figure 2 is a fragmentary view in vertical section partly broken away and taken on the irregular line 2—2 of Figure 1;

Figure 3 is an enlarged fragmentary view in horizontal section taken on the line 3—3 of Figure 1;

Figure 4 is a fragmentary enlarged view in side elevation partly in section;

Figure 5 is an enlarged fragmentary view in horizontal section taken on the line 5—5 of Figure 4, and

Figure 6 is an enlarged exploded view in perspective of parts of means operatively connecting the stop mechanism to the counter.

Referring to the drawings by numeral, according to this invention, a conventional rotation counting register 1, for instance of the well known cyclometer type, is suitably mounted in horizontal position on a bracket 3 rising from one side 5 of the press 7, shown fragmentarily as sufficient for the present purposes. The rotation counting register 1

2

is elevated above the stop mechanism 9 by the bracket 3 which is bolted, as at 6, to one side guard 8 of the press 7.

The impression cylinder 11, in a manner and by means well known in the art, is moved from a lowered idle position, shown in dot and dash lines in Figure 1, into a raised position, shown in dash lines in Figure 1, as said cylinder completes each printing cycle of operation in a direction, for instance that indicated by the arrow in Figure 1.

The stop mechanism 9 need merely be briefly described

10 herein since it is fully disclosed in the aforesaid patent. This stop mechanism comprises a collar 13 fixed on the cylinder shaft 15 and having a shouldered cam block 17 fixed thereon. The block 17, as the cylinder 11 moves into its raised position and rotates into its full cycle position 15 abuts upright leaf stop spring devices 19 bolted, as at 21, to an upright block 23 bolted, as at 25, to the side 5 of the press above the shaft 15, and said block 17 at the same time cams upwardly an upright stop rod 27 slideable in said block 23 and spring loaded to descend behind the shoulder 20 31 of the block 17 in the full cycle position of said cylinder 11 so that said cylinder is held against rotation for lowering into idle position. A setscrew 33 holds a threaded rod guide collar 35 in a bore 37 in the block 23 to retain a helical rod loading spring 29 in the bore. An adjusting nut 25 39 is threaded on the stop rod 27 above a washer 38 on the block 23 to variably tension the spring 29 between the guide collar 35 and a collar 40 fixed on the stop rod 27, said nut also providing for variably adjusting said stop rod 27 upwardly or downwardly as occasion may require for 30 wear take up purposes.

Means operatively connecting the stop mechanism 9 to the revolution counting register 1 comprises the following: A register operating push rod 41 extends upwardly from the stop rod 27 in axial alignment therewith and is vertically slideable in a pair of upper and lower vertically spaced bearings 43, 45 bolted, as at 44, 46, on the bracket 3 above the guard 8. The rotation counting

35 register operating push rod 41 seats on the stop rod 27 for movement upwardly thereby. A helical spring 47 surrounds the register operating push rod 41 between the upper bearing 43 and a set collar 49 on said rod 41 and tensions said rod against upward movement while maintaining said rod 41 seated on the stop rod 27. The set collar 49 seats on the lower bearing 45 and provides for

40 vertically adjusting the register operating push rod 41, as may be required, to take up wear in the operating means connecting the stop mechanism 9 to the rotation counting register 1. A slot 51 is provided in the guard 8 for extension of the register operating push rod 41 there-through above said guard.

45 A lever 53 above the register operating push rod 41 extends laterally across the same and is pivoted intermediate its ends, as at 55, on the bracket 3 for rocking in a vertical plane with said rod 41 underlying one end of said lever 53 to rock said lever 53 in one direction. A helical spring 57 rises from the lever 53 and is attached at its ends, as at 59, 61, to the other end of the lever 53 and to the conventional arm 63 on the revolution register 1 for operating the lowest denominational number wheel 50 65 of said register.

The operation of the invention will be readily understood. In response to movement of the impression cylinder 11 into its raised position and rotation of said cylinder into full cycle position, the stop rod 27 is cammed upwardly to slide the register operating push rod 41 upwardly against tension exerted by the spring 47. The push rod 41 rocks the lever 53 clockwise, as viewed in Figure 1, from a substantially horizontal position. Such

60 rocking of the lever 53 exerts pull on the spring 57 to cause operation of the rotation counting register 1 in a manner which will be understood to register the number of rotations of said cylinder and the number of sheets 65 70

or other work printed. As the stop rod 27 descends the register operating push rod 41 descends under the influence of the spring 47 and permits the lever to return, counterclockwise, into substantially horizontal position under the influence of the spring 57.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the invention as claimed.

What is claimed as new is as follows:

1. In combination with a printing press cylinder and a full cycle stop mechanism for said cylinder having a stop member movable upwardly in response to rotation of said cylinder into full cycle position, a rotation counting register for said cylinder, means mounting said register on the press remote from said cylinder, and means operatively connecting said stop member to said register to operate the register in response to upward movement of said member, said last named means comprising a push rod vertically slidably mounted on the press upwardly movable by said stop member from a lowered position, and a lever pivoted on said press for swinging in a vertical plane and having one end operatively engaged by said push rod for swinging thereby in one direction, and a helical spring operatively connecting the other end of said lever to said register.

2. The combination of claim 1, further including bearings on said press mounting said push rod, and a set

collar on said push rod seating on one of said bearings and establishing therewith a lowered position of said push rod.

3. The combination of claim 2, and spring means urging said push rod into lowered position.

4. In a printing press having a rotary impression cylinder mounted for linear reciprocation and having a stop mechanism for yieldably locking said cylinder against rotation after a full cycle movement of said cylinder, 10 said stop mechanism including a stationary casing and a latch element mounted therein and periodically movable through a stroke to periodically lock said cylinder against rotation after each cycle of movement thereof, a counter mechanism mounted in spaced relation to said 15 stop mechanism and adjustable means operatively interconnecting said latch element and counter mechanism and responsive to movement of said latch element through each stroke to operate said counter mechanism, said adjustable means including slide means spring biased into engagement with said latch element, lever means connected to said slide means and yieldable link means interconnecting said lever means and said counter mechanism.
